DENTAL LAVATORY

Bert B. Swinnerton, Tiffin, Ohio, assignor to
Standard Sanitary Manufacturing Company,
a corporation of New Jersey

Application November 25, 1936, Serial No. 112,717

10 Claims. (Cl. 4—166)

My present invention relates to sanitary fixtures and more especially to dental lavatories and the like.

Dental lavatories of the usual types have been used for many years and have generally been entirely satisfactory in their normal operation. Under abnormal conditions, however, such lavatories have a serious disadvantage in that they become a source of contamination of the fresh water supply. When such lavatories become clogged, as not infrequently happens, the water level rises to the top of the lavatory and if the water supply valves are opened while a negative pressure exists in the water supply system back-siphonage of waste matter from the lavatory into the water supply system unavoidably occurs. The disadvantages and dangers connected with such back-siphonage will be obvious but insofar as I am aware no provision has heretofore been made which will effectively and simply eliminate such back-siphonage.

It is accordingly one of the objects of my present invention to provide a dental lavatory which by its very construction will render back-siphonage into the fresh water supply impossible.

It is another object of my invention to provide a dental lavatory with a special wall structure which simply, efficiently and automatically prevents back-siphonage from the lavatory into the sources of fresh water supply.

A further object of my invention resides in making dental lavatories with an upstanding wall structure provided with a series of communicating chambers so constructed and arranged that upon the arising of abnormal conditions in the lavatory and water supply system a vacuum-breaking effect will be produced which will positively prohibit back-siphonage.

Other and further objects and advantages of my present invention will either be understood by those skilled in this art or will be apparent or pointed out hereinafter.

In the accompanying drawings forming a part hereof:

Figure 1 is a plan view of a dental lavatory embodying my present invention;

Fig. 2 is a front elevational view of the lavatory of Fig. 1;

Fig. 3 is a rear elevational view of my new lavatory with portions broken away to expose details thereof; and

Fig. 4 is a vertical sectional view taken on the line IV—IV of Fig. 2.

Like numerals designate corresponding parts throughout the several views of the drawings.

In general, my invention comprises a dental or other lavatory which is provided with an upstanding wall structure and wherein such wall structure is so cast or otherwise formed during the manufacture of the lavatory that a series of communicating openings and a spout are formed therein. These openings are so disposed and arranged that when the water level in the lavatory rises beyond a certain point and when the water supply valves are opened while a negative pressure exists in the water supply system, a venting will occur, thus breaking the vacuum or negative pressure in the water supply system and eliminating any possibility of back-siphonage from said lavatory to said water supply system.

Referring now to the drawings in detail, the numeral 10 indicates a hollow rim which is preferably but not necessarily made of vitreous china. The bore or cavity in the rim is designated by the numeral 11 and a plurality of circumferentially spaced washdown openings 12 are provided in the inner under side of the rim, thus giving communication between the cavity 11 in the rim and the bowl 13 located below the rim. The bowl 13 is likewise preferably made of vitreous china or similar material and is of conventional cup-shape; it is provided in its bottom with a plurality of drain openings indicated by the numeral 14.

Disposed beneath the said bowl 13 is the trap-forming member 15 likewise preferably made of vitreous material and likewise being generally cup-shaped. The trap-forming member 15 is provided with an aperture 16 in its bottom for the reception of a drain plug indicated by the numeral 17. Projecting downwardly from said vitreous bowl 13 is the seal wall 18. This seal wall projects into the trap-forming member 15 forming a seal passage 19. A vitreous web 20 extends from the trap and forms one side of discharge orifice 21. Extending from said bowl is another vitreous web 22 which, with web 20, completes the formation of the discharge orifice as will be clearly apparent from Fig. 4 in particular.

Rising from said bowl and rim is the upstanding vitreous wall structure 23 which terminates in a shelf top 24 as shown. This wall structure is so cast or formed during the manufacture of the lavatory that it is provided with a spout 25 and a series of communicating chambers to be hereinafter described. A water inlet opening 26 is provided in a thickened portion 27 of the wall structure 23 for the reception of a pipe fitting 28 adapted for connection with an associated source of water supply. Chamber 29 is adapted

to receive water from fitting 28 connected to the associated water supply system which is arranged to provide either hot or cold water to the lavatory or a mixture of hot and cold water and in the latter case chamber 29 also functions as a tempering or mixing chamber. This chamber 29 communicates with a second chamber 30 via the connecting apertures 31. It will be noted from Fig. 3 that the upper portion of chamber 30 is divided and is open to the atmosphere, thus providing vents which are indicated by the numerals 32. Water received by chamber 30 from chamber 29 passes into the hollow rim cavity 11 and thence via washdown openings 12 to the bowl for flushing and cleaning purposes.

Hot and cold water supply valves 33 are provided as shown, each of which is suitably connected by piping 34 to a suitable source of water in supply duct 35. The valves are operated by valve stems 36 which are, in conventional manner, provided with operating handles 37 and the valve stems 36 are also provided with the usual escutcheons 38. From the valves 33 slip pipes 39 lead to water supply inlet 28 and connection is made at the rear of the wall structure 23 at the thickened portion thereof by means of a suitable expansion joint indicated by the numeral 40. A suitable waste or discharge pipe is suitably connected in the usual manner to discharge orifice 21 heretofore mentioned and such pipe leads to any suitable sewer or discharge duct. Numeral 41 indicates a suitable connecting member for connection with such sewer or discharge duct.

35

Normal operation

In the normal operation of the dental lavatory the valves 33 are opened to the desired extent and this causes water to flow into chamber 29. 40 Where hot and cold water are both being utilized chamber 29 tempers or mixes the same and then divides the water into two paths or streams, one of which passes through the spout 25 and into the bowl of the lavatory and the other of which 45 passes via openings 31, chamber 30 and washdown openings 12 to the bowl 13 through the rim. Water drains into trapway 15 through drain openings 14 and thence to the discharge pipe, water normally standing in the trap-way 50 to the level shown in Fig. 4 for the usual purposes.

Abnormal operation

As not infrequently happens in connection 55 with dental or other lavatories, either the trapway, the drain openings or the washdown openings become clogged. In some cases also the sewer backs up or becomes clogged. In the event that any of these conditions arise water naturally rises in the lavatory until it covers the washdown openings 12. It not infrequently happens 60 also that a vacuum or negative pressure temporarily exists in the water supply pipes and/or system which may be due to a number of different factors. For example, repair work may be going on in connection with the water supply system and water may be in process of being drained from the system. In other cases, sudden large demand upon the water supply system, especially at a lower level than the lavatory, 65 likewise causes a negative pressure to arise in the water supply system. If the valves 33 are opened when the water level in the lavatory lies above the washdown openings and while a negative 70 pressure exists in the water supply system, in 75

prior known lavatories waste and water would be immediately back-siphoned from the lavatory into the water supply pipes, thus contaminating the source of fresh water supply. With the present construction, however, this is not possible 5 primarily because of the presence of vents 32 in the chamber 30. When the valves are opened under the abnormal conditions recited air is immediately and rapidly sucked in through said vent openings and finds its way through openings 10 31 into chamber 29 and thence into water supply pipes where it breaks the vacuum. Therefore, in a lavatory constructed as herein described, such back-siphonage from the lavatory into the water supply system is effectively eliminated. While a certain amount of air would, under the conditions named, be sucked in through spout 25, this in itself is insufficient to effect the purposes of the present invention.

From the foregoing description taken in connection with the drawings, the construction and operation both under normal and abnormal conditions of my present invention will be readily understood. I wish to point out, however, that the foregoing is intended more in an illustrative 25 than in a limitative or restrictive sense and that so long as I adhere to the general principles and considerations above set forth I may make certain variations, substitutions, alterations or omissions in the construction of any particular lavatory. While I have stated that the rim, bowl, trap-way and wall structure are preferably cast from vitreous china or other vitreous or silicious material, it is within the principles and scope of my present invention to make these members 35 of other materials such as suitable metals. While I have shown the rim, bowl, trapway and wall structure as being unitary or integral, I am not restricted in this because it is within the purview of my invention to make the lavatory in as many 40 parts as may be convenient or dictated by good judgment and experience and then to assemble the same into a complete unit. Rather, the scope of the invention is to be measured by the subjoined claims and all modifications indicated by 45 the foregoing or such as will be understood or appreciated by those skilled in this art are considered by me as a part of my present invention.

Having thus described my invention, what I claim as new and desire to secure by Letters Patent is:

1. A lavatory comprising a bowl having drain openings in its bottom, a trapway below said bowl and communicating with a waste outlet, a hollow rim superjacent said bowl and provided with circumferentially spaced washdown openings, a spout for supplying water to said bowl and means for irreversibly supplying water to said spout and to said rim.
2. A lavatory comprising a bowl having drain 60 openings in its bottom, a trapway below said bowl and communicating with a waste outlet, a hollow rim superjacent said bowl and provided with circumferentially spaced washdown openings, a spout for supplying water to said bowl 65 and means for irreversibly supplying water to said spout and to said rim, said means including a series of passageways interconnecting the water supply means with said rim, said spout and the atmosphere, whereby, irrespective of conditions in said lavatory and water supply means, back-siphonage from said lavatory to said water supply means is prevented.
3. A lavatory comprising a bowl having drain 70 openings in its bottom, a trapway below said bowl 75

and communicating with a waste outlet, a hollow rim superjacent said bowl and provided with circumferentially spaced washdown openings, a back wall rising from said rim and terminating in a shelf-top, a spout formed in said back wall, a chamber in said back wall communicating with said spout and with said hollow rim, means for supplying water to said chamber and means for preventing reversal of water flow irrespective of 10 conditions in the lavatory and water supply means.

4. A dental lavatory comprising a bowl having drain openings in its bottom, a trapway below said bowl and communicating with a waste outlet, a hollow rim superjacent said bowl and provided with circumferentially spaced washdown openings, a back wall rising from said rim and terminating in a shelf-top, a spout formed in said back wall, a chamber in said back wall communicating with said spout and with said hollow rim, means for supplying water to said chamber and means for breaking vacuum arising in the water supply means and for preventing the same from causing back-siphonage from said lavatory.

5. In a dental lavatory of the type described, a wall structure provided with a chamber for receiving and distributing water and a second chamber communicating with the first chamber, the second chamber being vented to the atmosphere.

6. In a dental lavatory having a hollow rim provided with washdown openings communicating with a subjacent bowl, a wall structure having a spout and a series of communicating chambers formed therein, one of said chambers being adapted to receive and distribute water from an associated source of water supply and another of said chambers being vented to the atmosphere.

7. In a dental lavatory having a hollow rim provided with washdown openings communicating with a subjacent bowl, an upstanding wall structure terminating in a shelf-top, said wall

structure having a spout formed therein and being provided with a series of communicating chambers interconnecting the spout and the washdown openings with a source of water supply, one of said chambers being vented to the atmosphere, said wall structure, under normal conditions, distributing water to said spout and said washdown openings and, under abnormal conditions, preventing back-siphonage into said water supply.

8. In a dental lavatory having a hollow rim provided with washdown openings communicating with a subjacent bowl, a wall structure having a spout and a series of communicating passageways formed therein, one of said passageways being adapted to receive water from an associated source of water supply and to distribute it to said spout and to another of said passageways which latter is vented to the atmosphere and adapted to deliver water to said washdown openings.

9. A lavatory comprising a bowl having drain openings, a hollow rim on said bowl provided with circumferentially spaced washdown openings, a back wall rising from said rim, a spout formed in said back wall, means for supplying water to said spout and to said washdown openings and means operative under all conditions for preventing back siphonage from said lavatory to said water supply means.

10. A lavatory comprising a bowl having drain openings in its bottom, a trapway below the bowl communicating with a waste outlet, a hollow rim on the bowl provided with circumferentially spaced washdown openings on its underside, a back wall rising from said rim and means operatively associated with said back wall to supply water to said bowl and said washdown openings and to prevent back siphonage of such water irrespective of conditions encountered in the use of the lavatory.

BERT B. SWINNERTON.
